Primary Examiner — Prabhakar Deshmukh

(74) Attorney, Agent, or Firm — Nixon & Vanderhye PC

(57) **CLAIM**

The ornamental design for a "jukebox," as shown and described.

DESCRIPTION

FIG. 1 is a front perspective view of a jukebox showing our new design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

FIG. 7 is a bottom plan view thereof.

The broken lines represent environmental features of the claimed design. None of the broken lines form part of the claimed design.
